UNITED STATES PATENT OFFICE.

LOUIS MASSUGER, OF LE VESINET, FRANCE.

HOOD LATCH.

Application filed October 31, 1924. Serial No. 747,104.

To all whom it may concern:

Be it known that I, LOUIS MASSUGER, a citizen of the French Republic, residing at Le Vesinet, Department of the Seine-et-Oise, in France, have invented certain new and useful Improvements in Hood Latches; and I do hereby declare the following to be a full, clear, and exact description of the invention, such as will enable others skilled in the art to which it appertains to make and use the same.

The present invention relates to a latch or fastener for hoods of any type, or for covers in general; its object consists essentially in the provision of a very simple strong clasp or latch which is economical in construction and exceedingly efficient in operation. This clasp or latch enables the hoods or covers to be rapidly and firmly locked upon their seatings, and as easily unlocked, as desired. This advantage is especially appreciable in the case of hoods for motor cars and like power driven vehicles, which hoods are often subject to chattering by reason of insufficient rigidity of the latching device. Furthermore this improved apparatus is inherently adapted for use as a lifting handle thus avoiding the necessity for applying to hoods or covers a member separately adapted for this purpose.

In the accompanying drawings:

Fig. 1 is a longitudinal section taken through the latch, while in its locked position.

Fig. 2 is a similar view of the latch in its unlocked position.

Fig. 3 is a section taken on the line 3—3 of Fig. 1.

Now referring specifically to the drawings; 1 indicates a movable portion of an automobile hood, adapted to be positioned against a stirrup 2, in which is mounted a rod 3, adapted to receive the hooked end 4 of the latching member, as will hereinafter be described.

A tubular casing 5 extends obliquely through the hood section 1, and is rigidly secured thereto in any desirable manner. A tubular member 13 is mounted within the casing 5, and adapted for longitudinal reciprocation therein. Opposite sides of the member 13 are slotted at 14, and the sides of the casing 5 are similarly provided with registering slots, the construction being clearly shown in Fig. 3, and a stop pin 15, carrying a block 16, is mounted for recipro-

cation in said slots. The block 16 is of disk-like formation, and conforms to the inner walls of the member 13, and serves as an abutment for the lower end of a coiled spring 21, to be hereinafter referred to.

The upper end of the member 13 is provided with a slot 17, which spirally extends around said member, and which is adapted to receive a pin 18, fixed to project from a stem 19 projecting through the outer end of the casing 5. A hand-wheel 8 is rigidly secured to the end of the stem 19, and a collar 20 is secured to the upper portion of the stem 19, and engages an inwardly extending flange 20', formed on the upper face of the casing 5, and limits outward movement of the stem 19.

The coiled spring 21 is mounted between the block 16 and the lower end of the stem 19, and is designed to retain the stem 19 in its uppermost position at all times, and to prevent any chattering of the latch.

In operation when it is desired to release the hook 4 from the rod 3, the wheel 8 is turned in an anticlockwise direction, thereby causing the pin 18 to ride in the slot 17 and forcibly causing the member 13, under the camming action of the pin and slot construction, to move downwardly, to the position shown in Fig. 2, when the section 1 of the hood may be lifted. A reverse rotation of the wheel 8 will manifestly operate to lift the member 13 to a position such that the hook 4 will engage the rod 3, as will be understood.

Modifications of the structure herein disclosed may be suggested to those skilled in the art, but my invention covers all embodiments falling fairly within the scope 95 of the appended claims.

I claim:

1. A latch for automobile hoods and the like comprising a tubular casing extending through a movable portion of the hood, a hook member movable longitudinally of the casing, a fixed element beneath the said hood portion and adapted for operative connection with said hook member, a stem rotatably carried by the casing, and pin and slot connections between the stem and the hook member, whereby rotation of the stem may cause the member to move longitudinally of the casing.

2. A latch for automobile hoods and the like comprising a tubular casing extending through a movable portion of the hood, a

- hook member movable longitudinally of the casing, a fixed element below said hood and adapted for operative connection with said hook member, a rotatable stem mounted within the casing, a spiral slot in said hook member, and a pin projecting from said stem and extending into said slot, whereby rotation of the stem will move the hook member longitudinally of said casing.
10. 3. A latch for automobile hoods and the like comprising a tubular casing extending through a movable portion of the hood, a hook member movable longitudinally of the casing, a fixed element below said hood and adapted for operative connection with said hook member, a rotatable stem mounted within the casing, a spiral slot in said hook member, a pin projecting from said stem and extending into said slot, whereby rotation of the stem will move the hook member longitudinally of said casing, and means for limiting the movement of said hook member.
15. 4. A latch for automobile hoods and the like comprising a tubular casing extending through a movable portion of the hood, a hook member movable longitudinally of the casing, a fixed element below said hood and adapted for operative connection with said hook member, a rotatable stem mounted within the casing, a spiral slot in said hook member, a pin projecting from said stem and extending into said slot, whereby rotation of the stem will move the hook member longitudinally of said casing, and means for limiting the movement of said hook member.
20. 5. A latch for automobile hoods and the like comprising a tubular casing extending through a movable portion of the hood, a hook member movable longitudinally of the casing, a fixed element below said hood and adapted for operative connection with said hook member, a rotatable stem mounted within the casing, a spiral slot in said hook member, a pin projecting from said stem and extending into said slot, whereby rotation of the stem will move the hook member longitudinally of said casing, and means for limiting the movement of said hook member.
25. 6. A latch for automobile hoods and the like comprising a tubular casing extending through a movable portion of the hood, a hook member movable longitudinally of the casing, a fixed element below said hood and adapted for operative connection with said hook member, a rotatable stem mounted within the casing, a spiral slot in said hook member, a pin projecting from said stem and extending into said slot, whereby rotation of the stem will move the hook member longitudinally of said casing, and means for preventing rotation of said hook member with respect to said casing.
30. 7. A latch for automobile hoods and the like comprising a tubular casing extending through a movable portion of the hood, a hook member movable longitudinally of the casing, a fixed element beneath the said hood portion and adapted for operative connection with said hook member, a stem rotatably carried by the casing, cam connections between the stem and the hook member, whereby rotation of the stem will cause the member to move longitudinally of the casing, and means for limiting the downward movement of said stem.
35. 8. A latch for automobile hoods and the like comprising a tubular casing extending through a movable portion of the hood, a hook member movable longitudinally of the casing, a fixed element beneath the said hood portion and adapted for operative connection with said hook member, a stem rotatably carried by the casing, cam connections between the stem and the hook member, whereby rotation of the stem may cause the member to move longitudinally of the casing, and means for limiting the downward movement of said stem, said means comprising a coiled spring bearing against the lower end of said stem and constantly exerting upward pressure upon the latter.
40. 9. In testimony whereof I hereunto affix my signature.
45. 10. LOUIS MASSUGER.

50. 6. A latch for automobile hoods and the like comprising a tubular casing extending through a movable portion of the hood, a hook member movable longitudinally of the casing, a fixed element below said hood and adapted for operative connection with said hook member, a rotatable stem mounted within the casing, a spiral slot in said hook member, a pin projecting from said stem and extending into said slot, whereby rotation of the stem will move the hook member longitudinally of said casing, and means for preventing rotation of said hook member with respect to said casing, said means comprising registering closed slots extending longitudinally of said casing and said member, and a pin riding in said slots.

55. 7. A latch for automobile hoods and the like comprising a tubular casing extending through a movable portion of the hood, a hook member movable longitudinally of the casing, a fixed element beneath the said hood portion and adapted for operative connection with said hook member, a stem rotatably carried by the casing, cam connections between the stem and the hook member, whereby rotation of the stem will cause the member to move longitudinally of the casing, and means for limiting the downward movement of said stem.

60. 8. A latch for automobile hoods and the like comprising a tubular casing extending through a movable portion of the hood, a hook member movable longitudinally of the casing, a fixed element beneath the said hood portion and adapted for operative connection with said hook member, a stem rotatably carried by the casing, cam connections between the stem and the hook member, whereby rotation of the stem may cause the member to move longitudinally of the casing, and means for limiting the downward movement of said stem, said means comprising a coiled spring bearing against the lower end of said stem and constantly exerting upward pressure upon the latter.

65. 9. In testimony whereof I hereunto affix my signature.

70. 10. LOUIS MASSUGER.
